(57) **CLAIM**

We claim the ornamental design for a television receiver, as shown and described.

DESCRIPTION

FIG. 1 is a front perspective view of a television receiver showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is an enlarged view of the encircled portion in FIG. 4;

FIG. 10 is an enlarged view of the encircled portion in FIG. 8; and,

FIG. 11 is a rear perspective view thereof in which the stand feature is shown in another position.

The dash-dash broken lines in the figures depict portions of the television receiver which form no part of the claimed design.

The dot-dot-dash broken lines encircling portions of the claimed design that are illustrated in enlargements form no part of the claimed design.

1 Claim, 9 Drawing Sheets
